HOLDER FOR DISPOSABLE DRINKING CUP

Paul Davis, Swampscott, Mass., assignor to Sweetheart
Plastics, Inc., Wilmington, Mass.

Filed May 2, 1973, Ser. No. 356,417

Term of patent 14 years

Int. Cl. D7—01

U.S. Cl. D7—70

FIG. 1

FIG. 2

FIG. 3

FIG. 4

FIG. 5

FIG. 6

FIG. 7

FIG. 1 is a side elevational view of a holder for disposable drinking cup showing my new design;

FIG. 2 is an end elevational view thereof looking from the right of FIG. 1;

FIG. 3 is a top plan view thereof;

FIG. 4 is a bottom plan view thereof;

FIG. 5 is an enlarged fragmentary cross-sectional view taken on section line 5-5 of FIG. 1;

FIG. 6 is an enlarged cross-sectional view taken on section line 6-6 of FIG. 1; and,

FIG. 7 is an enlarged cross-sectional view of the handle taken on section line 7-7 of FIG. 1.

I claim:

The ornamental design for a holder for disposable drinking cup, as shown.
